(57) CLAIM

The ornamental design for the front surface of an undergarment with a pocket, as shown and described.

DESCRIPTION

FIG. 1 is a perspective view of a first embodiment of a front surface of an undergarment with a pocket showing the new design;

FIG. 2 is a front view of an first embodiment of a front surface of an undergarment with a pocket showing the new design;

FIG. 3 is a perspective view of a second embodiment of a front surface of an undergarment with a pocket showing the new design;

FIG. 4 is a front view of an second embodiment of a front surface of an undergarment with a pocket showing the new design;

FIG. 5 is a perspective view of a third embodiment of a front surface of an undergarment with a pocket showing the new design;

FIG. 6 is a front view of an third embodiment of a front surface of an undergarment with a pocket showing the new design;

FIG. 7 is a perspective view of a fourth embodiment of a front surface of an undergarment with a pocket showing the new design;

FIG. 8 is a front view of an fourth embodiment of a front surface of an undergarment with a pocket showing the new design;

FIG. 9 is a front view of an fifth embodiment of a front surface of an undergarment with a pocket showing the new design; and

FIG. 10 is a perspective view of a fifth embodiment of a front surface of an undergarment with a pocket showing the new design.

FIG. 11 is a front view of a sixth embodiment of a front surface of an undergarment with a pocket showing the new design; and,

FIG. 12 is a perspective view of a sixth embodiment of a front surface of an undergarment with a pocket showing the new design.

The un-broken lines in FIGS. 1–12 represent design elements. The broken lines in all figures showing the remainder of the undergarment are for illustrative purposes only and form no part of the claimed design.
